ATTORNEY

UNITED STATES PATENT OFFICE.

ARTHUR JAMES ABEL, OF BROOKLYN, NEW YORK.

ATTACHMENT FOR INTERNAL-COMBUSTION ENGINES.

1,380,173.

Specification of Letters Patent. Patented May 31, 1921.

Application filed April 9, 1920. Serial No. 372,695.

To all whom it may concern:

Be it known that I, ARTHUR J. ABEL, a citizen of the United States, residing at Brooklyn, in the county of Kings and State of New York, have invented new and useful Improvements in Attachments for Internal-Combustion Engines, of which the following is a specification.

This invention relates to an attachment for internal combustion engines and has for its main object to provide means for returning a portion of the partly burned gases from the exhaust to the cylinder, thereby effecting a saving in fuel.

15 In the accompanying drawings:—

Figure 1 is a detached side elevation of my improvement and the parts of an internal combustion engine to which the same is connected.

20 Fig. 2 is a fragmentary sectional detail view showing the cylinder which forms part of my invention and the means for connecting the same to the muffler of the engine.

25 Fig. 3 is a sectional view taken substantially in line 3—3 of Fig. 1, and

Fig. 4, is a detail view of one of the straps whereby my device is supported by the muffler.

30 Like reference characters refer to like parts in all the figures.

Referring now to Fig. 1, 1 represents the exhaust from an internal combustion engine, 2 represents a pipe leading to the 35 muffler 3. 4 represents a cylinder comprising a jacket formed of drawn tubing and provided at its ends with flanged disks 5, said disks being provided with apertures near their center, one of said apertures leading to the open air and the other being connected by a pipe 6 (which may be a flexible tube if desired) to the carbureter 7. The cylinder 5 is provided with four screens 8 which may be formed by punching disks 40 as shown in Fig. 3. These screens or perforated disks may be secured to the interior of the cylinder 4 in any suitable manner. Riveted to the cylinder 4 is a saddle 9 which is securely attached to a flexible saddle 10 in any suitable manner as for instance by the posts 11. The saddle 10 is firmly secured against the muffler 3 by means of straps 12. A pipe 13 formed with a slight taper at its upper end connects the interior 45 of the muffler with the interior of the cylinder 4 so as to conduct partly burned gases from the muffler into the cylinder 4. This pipe 13 is beveled at its upper end so that it may be forced into the aperture in the muffler, thereby obtaining a tight fit. A 60 sheet of asbestos 14 is interposed between the saddle 10 and the muffler 3.

The straps 12, of which there are two pair, are secured to each other, in the following manner:—Each pair of straps comprises a 65 short strap and a long one, the short strap being provided with a substantially angularly bent member 15 and the longer strap provided with a somewhat similar member 16. The members 15 are riveted to their respective short straps but each of the members 16 is provided with two apertures or slots 17 and 18, through which the long strap is passed and doubled back on itself as clearly shown in Fig. 4. The two members 15 and 16 are drawn together by means of a bolt and nut. From this it will be readily seen that the saddle 10 may be secured to mufflers of different diameter by letting out or taken up the longer metal 70 straps 12. The saddle 10 is flexible so that upon drawing the straps together the saddle with the mechanism depending therefrom, is securely seated on the muffler.

An auxiliary air intake is provided between the pipe 6 and the carbureter 7 as shown in Fig. 1, said intake comprising a sleeve 19 secured to the pipe 6 and provided with holes and an over lying sleeve 20 also provided with holes which may be 80 brought to register with those in the sleeve 19 by turning the sleeve 20. A pin 21 secured to the sleeve 19 and positioned in a slot in the sleeve 20 limits the amount of rotation which may be given to the sleeve 20. 95

Briefly stated, the operation of the device is as follows:—The exhaust gases from the engine pass through the pipe 2 into the muffler 3 from which a portion of such gases is conducted into the cylinder 4 where 100 it is mixed with fresh air taken in through the aperture in the rear disk 5, the screens or perforated disks 8 preventing the passage of dust, carbon, etc., into the pipe 6 and the carbureter 7. In the carbureter 7 an added 105 amount of vapor will be given to the charge to be conducted to the cylinder of the engine for subsequent explosion.

While I have described what I consider to be the most desirable embodiment of my in- 110

vention, it is obvious that the details thereof may be varied without departing from the spirit of my invention. I therefore do not wish to be considered as limiting myself to the specific construction herein shown nor to anything less than the whole of my invention, as hereinbefore described and as hereinafter more particularly pointed out in the claims.

10 What I claim as new and desire to secure by Letters-Patent is:—

1. In an attachment for internal combustion engines, the combination of a cylinder for mixing partly burned gases and fresh air, a saddle secured to said cylinder, a saddle adapted to be secured against the muffler of an engine, means for securing said saddles to each other, and means operable to secure the second said saddle to the muffler of an engine.

2. In an attachment for internal combustion engines, the combination of a cylinder for mixing partly burned gases and fresh air, a saddle, secured to said cylinder, a saddle adapted to be secured against the muffler of an engine, adjustable means for securing said saddles to each other, and means oper-

able to secure the second said saddle to the muffler of an engine.

3. In an attachment for internal combustion engines, the combination of a cylinder for mixing partly burned gases and fresh air, a saddle secured to said cylinder, a saddle adapted to be secured against the muffler of an engine, adjustable means for securing said saddles to each other, and pairs of straps adapted to secure the second said saddle to the muffler of an engine.

4. In an attachment for internal combustion engines, the combination of a cylinder for mixing partly burned gases and fresh air, a saddle secured to said cylinder, a saddle adapted to be secured against the muffler of an engine, adjustable means for securing said saddles to each other, pairs of straps adapted to secure the second said saddle to the muffler of an engine, said straps being provided with adjustable elements so as to accommodate themselves to different sizes of mufflers.

In testimony whereof I have affixed my signature.

ARTHUR JAMES ABEL.
